UNITED STATES PATENT OFFICE.

CARL G. PRITCHARD, OF HIRAM, OHIO, ASSIGNOR, BY MESNE ASSIGNMENTS, TO HARRIS-SEYBOLD-POTTER COMPANY, OF CLEVELAND, OHIO, A CORPORATION OF DELAWARE.

PRINTING PRESS.

Application filed December 21, 1926. Serial No. 156,127.

My invention relates particularly to a web printing-press and more especially to web rotary presses for lithographic printing by offset impression.

5 The objects of my invention are, among other things, to provide an improved rotary press of this type for printing upon both sides of the web of paper or other impression receiving material operable in combination with any suitable delivery for the perfected web which may embody sheet-cutting devices and a folder whereby when the impression is thrown off the press the forward feed of the web may be simultaneously stopped through 10 the press and delivery to enable the printing and offset cylinders to be run to get up color while the sheet-cutting and folding mechanisms may continue in operation, but without forwarding the web through the press and 15 without printing on such web which is held stationary in the press and delivery while the web-cutters and folder continue in operation. A further object is to provide for moving and arranging the different parts of 20 the web delivery in connection with the stoppage of the forward feed of the web so that the different functions may be performed without disarranging the press and delivery elements or interfering with the threaded 25 web. A further feature is to provide improved web feeding and stopping devices actuated in unison by the tripping of the press so that the web stopping devices are 30 timed to come into operation slightly before the web-feeding mechanism shall release its pulling hold on the web to end the forward feeding. During this interval the web stopping devices will automatically permit the web held thereby to have a slight forward 35 movement until the complete stoppage of the web takes place, but will effectually prevent any backward run of such web whereby any crumpling or tearing of such part of the web in the delivery is avoided. In like manner 40 when the web-forwarding mechanism is brought back into operation along with the restoration of impression on the press, the web-stopping devices still in contact with the web do not in any way hinder the further advancement of the web through the press with the resumption of the printing and delivery of the web to the cutters.

45

50

With these and other objects in view, my invention comprises the constructions and

operating parts forming the press and delivery mechanisms herein shown and hereafter to be described as one embodiment of my invention, such other features being fully and specifically set forth in the appended claims.

55

60

The accompanying drawings show this embodiment of my invention in connection with a web offset press printing two colors on one side and a third color on the other side of the web, the same serving to explain the invention which is not restricted, however, to any particular form or type of printing press construction.

65

70

In the drawings, Fig. 1 is a side elevation of my improved delivery and web-manipulating devices shown when the press is in operation and the web is being forwarded through the cutters which subdivide the web into sheets;

75

Fig. 2 is a top plan view of the web-stopping devices;

Fig. 3 is an end view of the upper portion of the delivery shown in Fig. 1 when looking toward the left;

80

Fig. 4 is a side elevation of Fig. 3 with the parts shown when the press has been tripped and the web held stationary with the web-feeding mechanism out of operation;

85

Figs. 5 and 6 are detail views of the rock-arms for the web-stopping and web-forwarding devices;

85

Figs. 7 and 8 are detail views of the web-stopping roller and operating mechanism therefor; and

90

95

Fig. 9 is a diagrammatic side elevation of a web offset press embodying three printing couples and delivery provided with my improvements operable in conjunction with a folder and end delivery to carry off the folded sheets.

Similar numerals refer to similar parts throughout the several figures.

100

105

Referring to Figs. 1-4, the side-frames 10 and 11 of the delivery have journalled therein the shafts 12 and 13 which carry the cutting cylinders 14 and 15 respectively in which are affixed the transverse coacting cutting knives 16 and 17 for severing the web W into sheets. The cylinders 14 and 15 are driven in unison by the intermeshing gears 18 and 19 keyed to the shafts 12 and 13 respectively (Fig. 1). The shaft 12 is driven by the bevel gear 20 attached to this shaft which gear 20 engages

the bevel gear 21 fastened to the upper end of the vertical drive shaft 22 journaled in the bracket 23 secured to the side-frame 10.

The web W is drawn forwardly in the direction of the arrows or advanced through the delivery by the forwarding roller 24 mounted on the shaft 25 journaled in the side-frames 10 and 11 as shown in Figs. 1 and 3. The shaft 25 carries the pinion 26 meshing with the idler gear 27 mounted on the stub-shaft 28 journaled in the side-frame 10 which gear 27 engages with the gear 18 mounted on the shaft 12. By this mechanism the forwarding roller 24 for pulling the web W forwardly is rotated in the same direction and at the same peripheral speed as the cutting cylinders 14 and 15. Coacting with the web-forwarding roller 24 are two spaced-apart drop rollers 28^a and 29 (Fig. 3), which when pressing the web W against the roller 24 as shown in Fig. 1 cause the web to be pulled by the roller 24 to advance same through the delivery as shown in Fig. 1.

The drop rollers 28^a and 29 are pinned to the lower ends of the rock-levers 30 and 31 journaled on the rock-shaft 32 journaled in the side-frames 10 and 11 (Figs. 1, 3 and 4). Keyed to the shaft 32 on either side of the rock-levers 30 and 31 are the vertical forked brackets 33 and 34 respectively having the interiorly threaded blocks 35 and 36 at their upper ends. The upper ends 37 and 38 of the rock-levers 30 and 31 have bores cut therein through which pass the adjustable screw bolts 39 and 40 with their inner threaded ends coacting with the threaded blocks 35 and 36 respectively carried by the brackets 33 and 34. Coiled about the bolts 39 and 40 between the blocks 35, 36 and lever ends 37 and 38 are the helical springs 41 and 42 by which the pressure of the drop rollers 28^a and 29 on the web-forwarding roller 24 may be properly adjusted for different grades of paper stock by turning the knurled caps 43 and 44 affixed to the outer ends of the screw-bolts 39 and 40. The springs 41 and 42 also serve through their variably regulated tension to control the timing of the coaction of the drop rollers 28^a and 29 with the web W and their movement therefrom. A lost motion connection is provided between the arms 33, 34 and the arms 37, 38 by adjusting the screw-bolts 39, 40 whereby a space is provided between the reduced portion of the knurled heads 43, 44 and their respective arms 37, 38 (Fig. 1) showing such construction only as to the arm 37 and head 43. The rock-shaft 32 is actuated by the rock-arm 45 keyed to the shaft 32 which carries in its outer end the tubular housing 46 (Fig. 6). Passing through the housing 46 is the slidible pin 47 having coiled about its shank 48 the helical spring 49 one end of which bears on the shoulder encircling the base 50 of the pin plug end 51, while the other end of the spring 49 bears

against the bottom of the cylindrical bore cut in the housing 46. The pin plug end 51 is adapted to engage either the upper hole 52 or lower hole 53 formed in the face-plate 54 of the rock-arm 55 journaled on the rock-shaft 32. By this mechanism the drop rollers 28^a and 29 may be placed in operative position against the web W as shown in Fig. 1 with the upper hole 52 engaged by the plug end 51, or the drop rollers 28^a and 29 may be swung away, and held in inoperative position with respect to the forwarding roller 24 by lowering the rock-arm 45 so that the plug end 51 shall slip into and engage the lower hole 53 when the drop rollers 28^a and 29 clear the web in all positions of the rock-levers 30 and 31. The pin 47 carries the knurled cap 56 (Figs. 5 and 6) so that the pin 47 may be properly manipulated to shift the plug end 51 from either hole 52 or 53 to the other as required.

As shown in Figs. 1 and 4, the web W passes upwardly from the press (Fig. 9) in the direction of the arrows over the compensating roller 57 by which the tension of the web W as it passes through the delivery is regulated. This roller 57 is pivoted to the end of the rock-arm 58 affixed to the shaft 59 journaled in the side-frames 10 and 11. Keyed to the shaft 59 is the rock-arm 60 having the interiorly threaded block 61 affixed thereto. Engaging the threaded block 61 is the threaded tip 62 of the rotatable rod 63 journaled in the bracket 64 and operated by the handle 65 affixed to the lower end. By this mechanism the operator may suitably adjust the tension of the web W by shifting the position of the roller 57 in rotating the rod 63 through the block 61 in either direction.

When the web-forwarding devices comprising the driven roller 24 and drop-rollers 28^a and 29 are separated and let go of the web W when the press is tripped, novel means are provided whereby such web shall be simultaneously or previously under the control of a suitable brake or stopping device so that such web W shall cease its forward travel and thereafter may be prevented from backing up or becoming misplaced in the delivery. In the present embodiment best shown in Figs. 1, 2, 3 and 4, the side-frames 10 and 11 carry the upright bearings 66 and 67 respectively in which is journaled the cross-shaft 68 carrying the idler roller 69 over which the web W passes before its downward run through the web-forwarding devices hereinbefore described. One end of the shaft 68 carries the ratchet 70 which is adapted to be engaged by the pawl 71 pivoted to the upright bracket 72 which is a continuation of the bearing 67. When the press is in operation the pawl 71 is held out of engagement with the ratchet 70 by the control disk 73 (Fig. 1) journaled on the shaft 68, thereby

permitting the web W in its forward travel to run freely over the roller 69 without any noise from the pawl 71 dropping over the teeth of the ratchet 70. Coacting with idler 5 roller 69 are two spaced-apart lock-wheels 74 and 75 pivoted to the inner ends of the rock-levers 76 and 77 rotatably mounted on the rock-shaft 78 which is journaled in the extension brackets 79 and 80 of the side frames 10 10 and 11 respectively. Keyed to the shaft 78 on either side of the rock-levers 76 and 77 are the horizontally extending forked brackets 81 and 82 respectively having the internally threaded blocks 83 and 84 on their 15 outer ends. The upper ends 85 and 86 of the rock-levers 76 and 77 have vertical bores cut therein through which pass the adjustable screw-bolts 87 and 88, with their threaded ends coacting with the threaded blocks 83 20 and 84 respectively of the brackets 81 and 82 (Figs. 1 and 3). Coiled about the bolts 87 and 88 between the blocks 83 and 84 and lever ends 85 and 86 are the helical springs 89 and 90 by which the pressure of the lock-wheels 25 74 and 75 on the idler rollers 69 and the timing of the movement of such lock-wheels against the web W may be suitably regulated by turning the knurled caps 91 and 92 affixed to the tops of the screw-bolts 87 and 88. The 30 rock-shaft 78 is actuated by the rock-arm 93 keyed to such shaft and the outer end of the rock arm 93 carries the tubular housing 94 (Fig. 6). Passing through the cylindrical bore of the housing 94 is the slideable pin 95 35 having coiled about its shank 96 within the housing bore the helical spring 97 one end of which bears on the shoulder 98 encircling the base 99 of the plug end 100, while the other end of spring 97 bears against the bottom of 40 the housing bore (Fig. 6). The pin plug end 100 is adapted to engage either the upper hole 101 or lower hole 102 cut in the face plate 103 of the rock-arm 104 journaled on the rock-shaft 78. By this mechanism the lock 45 wheels 74 and 75 may be placed in operative position with the idler roller 69 (Fig. 4) when the lower hole 102 is engaged by the plug end 100 or the lock wheels 74 and 75 may be shifted and lifted to inoperative position 50 even when the press is tripped (Fig. 4), by having the plug end 100 engage the upper hole 101. The pin 95 carries the knurled cap 105 (Figs. 2 and 3) by which the pin 95 may be properly manipulated to shift the plug end 55 100 from either hole 101 or 102 to meet the requirements of proper operation.

The tips of the rock-arms 55 and 104 are connected by the link 106 and the rock-arm 106 is also connected to the arm 107 of the 60 control disk 73 by the link 108. The rod 109 pinned to the rock-arm 55 is connected with the throw-off mechanism of the press shown in Fig. 9.

Referring to Fig. 9, the web offset press 65 therein shown in more or less diagrammatic form comprises three printing couples A, B and C of which couples A and B are adapted to print on one side of the web W, while couple C prints a single color on the opposite side so as to perfect the web. The particular form and arrangement of the printing couples and their connecting throw-off mechanisms for tripping the press are not important and in themselves do not constitute my invention. In Fig. 9 couples A and B are 70 built as a five-cylinder unit with form-cylinders D and E, transfer cylinders F and G and a common impression cylinder H, all of which are of equal diameter and are geared together to rotate in unison. Power is supplied to the press from the line shaft 110 carrying the bevel gear 111 meshing with the intermediate gear 112 connected with the gearing on the impression cylinder H. The printing couple C comprises the form cylinder I, 75 transfer cylinder J and impression cylinder K, all of like diameter and geared together to rotate in unison by power derived through intermediate gear 113 connected with the impression cylinder K and bevel gear 114 affixed to the line shaft 110. The form cylinders D, E and I have suitable inking and water dampening mechanisms as shown, while the transfer cylinders F, G and J and the impression cylinders H and K are all mounted in eccentric bearings provided with the usual throw-off and throw-on mechanisms to trip the press as well as to restore impression in the customary manner by the operation of the trip-lever 115 adjacent the transfer cylinder G. The trip-lever 115 is connected by link 116 to line shaft 117 and the trip mechanism for printing couple C is connected by link 118 to line shaft 117. The rocking of line shaft 117 when the press is tripped simultaneously lowers the rod 109 connected with my improved delivery as hereinbefore described. The web W (shown by dash and dot line) is fed to the press from the usual paper roll R around the impression cylinder H and thence is led to printing couple C whereby the web W is perfected with two colors on one side and one color on the reverse side. The printed web W is then passed over suitable idler rollers until it appears on the left side of Fig. 1 to be advanced through my improved web-stopping and web-forwarding devices hereinbefore described operating in conjunction with the cutting cylinders 14 and 15. After the printed web W has been severed into sheets the latter are carried to the collecting cylinder L and then to the folder M which deposits the folded sheets on the flat end delivery N in the usual way.

The operation of my improved delivery in connection with the web offset press shown in Fig. 9 is substantially as follows: Fig. 1 illustrates the position of the various parts when the press is in operation and the web W is running freely over the idler roller 69 with the

lock wheels 74 and 75 raised to inoperative position, the web being pulled forwardly by the drop rollers 28^a and 29 pressing the web W against the forwarding roller 24. Such web W then drops down into the bite of the cutting cylinders 14 and 15 which severs same into sheets that are then carried to the collecting cylinder L, folder M, and end delivery N as hereinbefore described. When the press 10 is tripped the connecting rod 109 is lowered and pulls down the rock-arms 55 and 104 which are connected by the link 106. This movement of the rod 109 first takes up the lost motion connection (Fig. 1) between the arms 15 33, 34 and 37, 38 and thereafter compresses the springs 41, 42 and releases the springs 89, 90, and then throws the drop rollers 28^a and 29 out of contact with the forwarding roller 24, but before these web advancing rollers become ineffective the lock wheels 74 and 75 are, by the same movement of the rod 109, brought down into contact with the idler roller 69 as shown in Fig. 4, and also the link 108 depresses the arm 107 of the control 20 25 disk 73 so as to bring the pawl 71 into engagement with the ratchet 70 thereby preventing the idler roller 69 from running backwardly or in anticlockwise direction. As shown in Fig. 4 the web W is held by the lock wheels 30 35 40 45 50 55 60 65 70 75 80 85 90 95 100 105 110 115 120 125 130 135 140 145 150 155 160 165 170 175 180 185 190 195 200 205 210 215 220 - press and delivery and separate means rotatable in one direction only contacting with the web for preventing a backward movement of the web while permitting a forward run thereof.
8. In a delivery for web printing-presses, a trip mechanism for the press, means for advancing the web through the press and delivery, and means for preventing a backward movement of the web through the delivery while permitting its forward feed, both said means being controlled by said trip mechanism.
9. In a delivery for web printing-presses, a trip mechanism for the press, means for advancing the web through the press and delivery, and means for preventing a backward movement of the web through the delivery while permitting its forward feed, said means being controlled in reverse order by said trip mechanism.
10. In a delivery for web printing-presses, a trip mechanism for the press, means for advancing the web through the press and delivery, and separate means for preventing a backward movement of the web through the delivery while permitting its forward feed, said means being controlled in reverse order by said trip mechanism.
11. In a delivery for web printing-presses, means for advancing the web through the press and delivery, means for rendering said web-advancing means ineffective, and means comprising coacting lock-wheels for preventing a backward movement of the web while permitting a forward run thereof irrespective of the action of said web-advancing means.
12. In a delivery for web printing-presses, a trip mechanism for the press, means for advancing the web through the press and delivery, means for rendering said web-advancing means ineffective, and means brought into action by said trip mechanism for preventing a backward movement of the web while permitting a forward run thereof irrespective of the action of said web-advancing means.
13. In a delivery for web printing-presses, means for continuously advancing the web through the press and delivery, means for cutting the web into sheets beyond said web-advancing means, and means for rendering said web-advancing means ineffective while allowing the web-cutting means to continue in operation.
14. In a delivery for web printing-presses,
- a trip mechanism for the press, means for advancing the web through the press and delivery, means for cutting the web into sheets beyond said web-advancing means, and means brought into action by said trip mechanism for rendering said web-advancing means ineffective and preventing a backward movement of the web while allowing the web-cutting means to continue in operation.
15. In a delivery for web printing-presses, a trip mechanism for the press, means for advancing the web through the press and delivery, means for cutting the web into sheets beyond said web-advancing means, means for preventing a backward movement of the web through the delivery while permitting its forward feed and continuing said web-cutting means in operation, and operative connections between said trip mechanism and both the web-advancing means and the means for preventing a backward movement thereof.
16. In a delivery for web printing-presses, means for advancing the web through the press and delivery, means for preventing a backward movement of the web while permitting a forward run thereof, and means for placing either of said last-mentioned means in inoperative position.
17. In a delivery for web printing-presses, means for advancing the web through the press and delivery, means for preventing a backward movement of the web while permitting a forward run thereof, and separate means for placing each of said last-mentioned means in inoperative position.
18. In a delivery for web printing-presses, a trip mechanism for the press, means for advancing the web through the press and delivery, means for preventing a backward movement of the web while permitting a forward run thereof, both said means being controlled by said trip mechanism, and means for placing either of said last-mentioned means in inoperative position irrespective of the action of said press trip mechanism.
19. In a delivery for web printing-presses, a trip mechanism for the press, means for advancing the web through the press and delivery, means for preventing a backward movement of the web while permitting a forward run thereof, both said means being controlled by said trip mechanism, and separate means for placing each of said last-mentioned means in inoperative position irrespective of the action of said press trip mechanism.

CARL G. PRITCHARD.
